OSCAR WIEDERHOLD, OF JERSEY CITY, NEW JERSEY.

VAPORIZING-BURNER.

1,263,978.

Specification of Letters Patent.

Patented Apr. 23, 1918.

Application filed June 23, 1916. Serial No. 105,394.

To all whom it may concern:

Be it known that I, OSCAR WIEDERHOLD, a citizen of the United States, and a resident of Jersey City, in the county of Hudson and 5 State of New Jersey, have invented certain new and useful Improvements in Vaporizing-Burners, of which the following is a specification.

My present invention relates to burners in 10 which liquid fuel, say kerosene, is vaporized and the vapor, mixed with air, burned to produce heat, say for bringing a so-called incandescent mantle to luminosity. In devices of this class, means are generally provided for conducting a portion of the heat developed by combustion, to the fuel which is on its way to the burner, so that such fuel may become heated and vaporized. A primary object of my present invention is to 15 provide a very efficient and simple device for thus conveying the heat of the flame to the supply of fuel flowing to the burner. Another feature of my invention relates to means for the thorough and energetic mixing 20 and preheating of the air and vaporized fuel. Still another feature of my invention has for its object to facilitate the cleaning of the fuel-outlet, so as to readily keep the burner in properly operative condition. 25 Other features of the invention will appear from the description following hereinafter, and particularly from the appended claims, which define the scope of my invention.

Reference is to be had to the accompanying drawings, which illustrate, as an example, a kerosene-vapor burner in connection with an incandescent mantle of well-known character, said burner embodying the features of my present invention. In these 30 drawings Figure 1 is a central sectional elevation of the appliance, taken on line 1—1 of Fig. 2; Fig. 2 is a horizontal section on line 2—2 of Fig. 1; Fig. 3 is a vertical section on line 3—3 of Fig. 2; and Fig. 4 is a vertical section on line 4—4 of Fig. 1.

Fuel is supplied in any well-known or approved manner to the lower end of the supply-tube A; if this fuel is kerosene, it would be supplied from a reservoir in which it is 45 kept under pressure; such reservoir and the means for producing pressure therein, being well-known in the art, I have not deemed it necessary to show them in the drawing. A' is a nipple for connecting the tube A with the pipe leading from the reservoir. The upper end of the supply-tube A is shown

screwed into a short vertical tube B extending downwardly from the central portion of a horizontal fuel-heating or vaporizing tube C. A piece of wire-gauze or the like is rolled at 50 D, in such a manner as to leave a longitudinal central passage d, and placed within the horizontal tube C, and a similar piece of rolled or coiled wire-gauze D' is placed in 55 the short vertical tube B, the two rolls or coils being preferably in contact with each other, and the upper end of the tube A serving to press the coil D' into contact with the coil D, or at least to hold the vertical coil 60 stationary. The horizontal coil D abuts at the right-hand end against the wall of the tube C, while the other end of said coil is engaged by a screw-plug E, screwed into 65 said tube C so tightly as to prevent leakage 65 and also to prevent loosening of the plug. At the right-hand end of the horizontal fuel-heating tube C, I have shown an upright tube F, which may be integral with the tubes B and C, and the lower end of the 70 tube F communicates with the tube C. At the upper end of the tube F I provide a laterally-arranged nozzle H having a horizontal outlet H'. Opposite this outlet, but spaced therefrom, is arranged a horizontal 75 mixing tube J, open at both ends, and suitably supported, as by passing through the intermediate member K of a shell or body, which as shown comprises cylindrical members K', K, K'' of different diameters, an 80 annular horizontal member K* connecting the lower, widest member K' with the intermediate member K, and an annular horizontal member K^a at the junction of the said intermediate member K with the upper, narrowest member K''. The heating tube C extends through or against the lowermost cylindrical member K' and is secured thereto, as by a nut G screwing on the plug E. This member is open at the bottom, as shown, so 85 that the flame of alcohol or other suitable fuel burning in the cup L (carried by the tube A) may pass into the shell or body and strike the tube C, to preheat it in the well-known way when starting the burner or 90 lamp. The upper end of the shell or body is also open and receives the sleeve M of the burner having a perforated arched plate M', an annular portion M'', and an outer cylindrical flange M*. The lower edge of the incandescent mantle N is received between the 95 said flange M* and the sleeve M, and said 100

mantle is supported in any suitable manner, for instance by means of a vertical rod O (of refractory material) carried by the center of the burner plate M' and engaging the upper end of the mantle N at its center.

Within the intermediate member K of the shell or body, and below the mixing tube J, is secured a horizontal disk or plate P, which closes the lower end of said intermediate member, except that a central strip or band of perforations P' is provided in said plate. The horizontal annular member K* is provided with a segmental opening k immediately below the mixing tube J and 10 symmetrically with reference thereto (see Fig. 2), and above the said annular member, adjacent to said opening, extends vertically a wall Q, Q', the outer portion of which, Q, is curved concentrically with the shell or body, while the end portions, Q', extend radially to the intermediate member K at their lower ends, and to the cylindrical flange M* at their upper ends. From the lower end of the wall Q, Q' extends outward horizontally a plate R, which may be 20 made integral with said wall, and the outer portion of which, R', straddles the vertical tube F and is preferably inclined upwardly and outwardly, as shown. The annular member K*, at its opening k, forms the bottom of a chimney extending upwardly between the wall Q, Q' and the adjacent portion of the shell or body, and preferably terminating at about the level of the upper 30 edge of the flange M*, the latter is preferably apertured where it forms part of the chimney wall, as indicated at m, for a purpose stated hereinafter. The lowermost body member K' is provided with a lateral opening k' which serves to facilitate the assembling of the device and also allows some of the hot gases to pass out, under the wall or shield R, R' to heat the right hand end of the tube C, and the upright tube F, as 40 will be explained below. The mixing tube J also extends through the wall Q, and is preferably secured thereto, so that the mixing tube is supported by the member K and by the wall Q. The plate R is shown as 45 extending into a slot of the vertical tube F, so that said plate, in conjunction with the material or lug F' above said slot, serves as an additional support for the connected tubes B, C, F.

50 In operation, the lamp is started by pouring fuel, say alcohol, into the cup L, and lighting such fuel. The flame will strike and heat the tubes B, C, together with the lower portion of the tube F, the opening k' allowing the flame to spread laterally for this purpose, while the shield R, R' prevents such flame from reaching the fuel nozzle H. The fuel in the tubes B, C, F will be vaporized or preheated, this action being intensified by the state of fine subdivision obtained

by the use of the wire-gauze coils D, D'. The vaporized fuel will pass out through the nozzle H, become mixed with air (streaming chiefly from above and from the sides), and flow through the mixing tube J, 70 in which the vaporized or heated fuel will become thoroughly mixed with the air. Issuing from the delivery end of the mixing tube, the air-and-fuel mixture will impinge against the wall K, which will deflect it laterally to both sides, and the whirling action thus obtained will contribute to still further insure the homogeneousness of the mixture. The chamber located between the burner plate M' and the perforated plate P, and 80 surrounded by the members K', K, K'' and M, forms a mixing chamber communicating with the mixing tube J, which latter may therefore be considered as forming part of the mixing chamber. The mixture of gas 85 or vapor and air passes out of said chamber, partly through the perforated burner plate M', and partly through the perforations P' in the plate or disk P at the bottom of the mixing chamber. These perforations P' 90 are preferably located exactly above the fuel-heating or vaporizing tube C, so that the gas or vapor issuing from the perforations P' will strike said tube C, which is located a slight distance below the perforations, and moreover, the gas or vapors will stream around the sides of said tube C. The flame from the cup L will come in contact with the mixture issuing from said perforations P', and will ignite such mixture. 95 The plate P therefore forms an inverted burner the flame of which will heat the tube C. As soon as this flame is lighted (which will take place automatically) there is no further need of heating by the flame from the starting cup L, and the latter flame can 100 be extinguished, or allowed to go out. The combustion products from the inverted flame at the perforations P' will escape partly through the lateral opening k' and under the shield R, R', but chiefly through the chimney connected with the opening k. It will be understood that only a small portion of the mixture contained in the mixing chamber will pass downwardly through the 110 perforations P', the larger part passing up through the burner plate M' to the mantle, where it is ignited in the usual way. The shield R, R' not only concentrates the heat of the starting flame and of the inverted 115 burner flame upon the lower portion of the upright tube B and the adjacent end of the horizontal tube C, but likewise keeps the said flames from reaching the nozzle H and from contaminating the fuel issuing therefrom, or even causing a premature ignition of such fuel. The inverted burner flame will, under normal conditions, continue to burn as long as the lamp is in operation, and will thus constantly heat or vaporize the 120

125

130

fuel flowing through the tube C on the way to the mixing chamber. However, should the inverted flame go out accidentally, an unconsumed portion of the fuel-and-air mixture will pass through the perforations P' around the tube C, and up the chimney communicating with the opening h, said chimney terminating adjacent to the mantle. Since the latter will remain incandescent for a while even in the event of the fuel-heating flame at P' going out, the unconsumed mixture issuing from the upper end of said chimney will become ignited by contact with the incandescent mantle, and the flame will jump back downwardly in the chimney and right to the perforations P', so that the inverted burner will be re-lighted automatically. This re-lighting may be facilitated by providing apertures 20 in the inner wall of the chimney, as at m, so that the unconsumed mixture may reach the incandescent mantle N without requiring to travel to the top of the chimney.

It will be observed that there is a space 25 between the outlet of the nozzle H and the inlet of the mixing tube J. This is also of advantage as it affords facility for introducing a tool, such as a bar with a needle at the end, for cleaning the outlet H' of the nozzle H.

The flange M* forms a protector surrounding the edge of the mantle N and preserving it against injury by knocking against it. It will be seen that the edge of the mantle 35 is received in an annular trough formed by the parts M, M'', M*.

It will be obvious that my invention may be used not only for vaporizable (liquid) fuel, but for gaseous fuel as well, and likewise, that it is not limited in its application, to incandescent fuel lamps, although I prefer to use my present improvements in connection with incandescent fuel lamps burning kerosene.

Various modifications may be made without departing from the nature of my invention as defined in the appended claims.

I claim as my invention:

1. In conjunction with a mixing chamber having burner-forming top and bottom walls and a vertical wall between the levels of said burners, a mixing tube extending into said chamber horizontally and having its outlet adjacent to said vertical wall, the other end of said tube being open to the outside air, a vaporizer exposed to the heat of the lower

burner, and a nozzle connected with said vaporizer and adapted to inject vapor into said mixing tube.

2. In conjunction with a mixing chamber 60 having an upper burner and a perforated bottom forming a lower burner, and a deflecting wall between said burners, a mixing tube extending into said chamber over the perforated bottom thereof and terminating 65 adjacent to said deflecting wall, the other end of said tube being open to the outside air, a vaporizer exposed to the heat of the lower burner, and a nozzle connected with said vaporizer and adapted to inject vapor 70 into said mixing tube.

3. In conjunction with a mixing chamber having an upper burner and a perforated bottom forming a lower burner, a mixing tube extending longitudinally above the perforated bottom of said chamber and having 75 its discharge end within said chamber, and means for supplying fuel to said mixing tube.

4. In conjunction with a mixing chamber 80 having burners at the top and bottom respectively and a curved vertical deflecting wall between the levels of said burners, a mixing tube extending into said chamber and having its outlet adjacent to, and directed 85 horizontally against, said curved deflecting wall, the other end of said tube being open to the outside air, a vaporizer exposed to the heat of the lower burner, and a nozzle connected with said vaporizer and located 90 to inject vapor into said mixing tube.

5. In conjunction with a mixing chamber having an upper burner and a perforated bottom forming a lower burner, a mixing tube extending within said chamber between 95 the said burners and over said perforated bottom lengthwise, a vaporizer exposed to the heat of said lower burner, and a nozzle connected with said vaporizer and located 100 to inject vapor into said mixing tube.

6. In conjunction with a mixing chamber having a mantle-heating burner at its upper portion and a fuel-heating burner at its lower portion, an annular trough arranged to receive the edge of the mantle, the outer 105 wall of said trough being perforated, and a chimney leading from a point adjacent to said fuel-heating burner upwardly and along the perforated portion of said trough.

In testimony whereof, I have signed this 110 specification.

OSCAR WIEDERHOLD.
